UNITED STATES PATENT OFFICE

JESSE G. KING, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed December 30, 1927. Serial No. 243,699.

This invention relates to a refrigerator having ice-forming compartments.

An object of this invention is to construct a refrigerator of the mechanical refrigerated type provided with an ice-forming compartment into which the drip from the cooling unit is prevented from flowing into the ice-forming compartment.

Another object of this invention is to provide an ice tray adapted to fit into a cooling unit in such a manner that drip from the cooling unit does not flow into the ice tray.

Further object and advantages of the present invention will be apparent from the following description, reference being had to the accompanying drawing, wherein a preferred form of the present invention is clearly shown.

In the drawings:

20 Fig. 1 shows a vertical cross sectional view partly in elevation of a refrigerator embodying my invention;

Fig. 2 shows a top elevation of an ice tray embodying my invention;

25 Fig. 3 shows a side elevation of the ice tray;

Fig. 4 shows an end elevation, and

Fig. 5 shows a side elevation of a modification embodying my invention.

30 A refrigerator embodying my invention, generally designated as 21, may have a cooling unit in a compartment, which cooling unit is generally designated as 22, and may be supported in the refrigerator by any suitable means generally designated as 23. The front of the cooling unit may be encased by a partition 24 having openings 25 through which ice trays generally designated as 26 may be inserted. The cooling unit may be 35 further provided with sleeves 27 for the reception of the ice trays 26 within the cooling unit. These sleeves 27 are adapted to cover the body of the ice trays in order to prevent the drip from the cooling unit from entering the ice tray. A portion of the tray however, extends beyond the sleeves 27 and drip is liable to fall on this extension as will appear hereinafter.

An ice tray embodying my invention may 30 comprise an ice compartment 30, adapted to

receive ice cube forming means, surrounded by walls 31 having a bead on top, designated as 32. The bead extends preferably, but not necessarily around the entire top. The handle 33 of the ice tray may be integral with the bead 32 and has a horizontal portion 34 below the top surface of the ice tray. The handle 33 may extend horizontally for a distance as shown at 34 and then extend vertically for a distance as shown at 35 and then again extend horizontally as at 36, which last named extension may be secured to the body of the tray at 37 by any suitable means, such as by soldering. The vertical portion 35 of the handle may be provided with an ornamental sealing cover 38 having a recess 39 for the reception of the fingers of the hand and this ornamental cover 38 may be secured to the handle 33 by means of bolts 40. By reference to Fig. 1 it is seen that handle 33 extends outside the sleeve 27 and that the handle 33 is left unprotected and that drip from the cooling unit may fall on this handle. As the horizontal portion 34 is below the level of the top of the ice tray the drip does not flow into the main body 30 of the ice tray. The tray with its handle may be pressed from a single piece of sheet metal, and the handle may be formed as shown after pressing.

In the modification shown in Fig. 5, a portion of the handle 33 need not be integral with the material of the body of the ice tray. At the horizontal extension 34' the handle may be of separate pieces secured together as by riveting means 44. The other horizontal 35 extension 36 of the handle 33 may be secured to the body of the tray by riveting means 41.

While I have shown the cooling unit as made of coils to which the sleeves 27 are secured it is to be understood that the exact 30 construction of the cooling unit herein shown is not a necessary feature of my invention.

While the form of embodiment of the invention as herein disclosed, constitutes a preferred form, it is to be understood that other 35 forms might be adopted, all coming within the scope of the claims which follow.

What is claimed is as follows:

1. An ice tray for a refrigerator comprising a pan having a bead on the top edge at one 100

- end, and a flat handle extending from said bead below the top thereof whereby drip on said handle from said refrigerator does not flow into said tray.
5. 2. An ice tray for a refrigerator comprising a pan having a flat handle connected to said pan below the top thereof, whereby drip on said handle from said refrigerator does not flow into said tray.
10. 3. A portion of a refrigerator comprising a sheet metal ice tray having an integral bead at the top, and an integral handle on said bead below the top of the tray, whereby drip in said refrigerator falling on said handle does not flow into said pan.
15. 4. A portion of a refrigerator comprising a sheet metal ice tray having an integral flat handle connected to the body of the tray below the top thereof whereby drip in said refrigerator falling on said handle does not flow into said tray.
20. 5. An ice tray for a refrigerator comprising a sheet metal tray body having an integral bead at the top, an integral flat handle connected to said bead below the top of said tray, said handle being bent upon itself and again secured to the body of said tray.
25. 6. An ice tray for a refrigerator comprising a sheet metal tray body having an integral bead at the top, an integral flat handle connected to said bead below the top of said tray, said handle being bent upon itself and again secured to the body of said tray, and a sealing cover secured to said handle.
30. 7. An ice tray for a refrigerator comprising a pan having a bead on the top edge at one end, and a flat handle extending from said bead below the top thereof whereby drip on said handle from said refrigerator does not flow into said tray, said handle including a horizontal portion adjacent said bead and a vertical portion depending from said horizontal portion and a vertical sealing cover secured to said vertical portion of the handle.
35. 8. An ice tray for a refrigerator comprising a pan having a bead on the top edge at one end, and a flat handle extending from said bead below the top thereof whereby drip on said handle from said refrigerator does not flow into said tray, said handle including a horizontal portion adjacent said bead, a vertical portion depending from said horizontal portion, and a lower horizontal portion extending from said vertical portion to said pan.
40. 9. An ice tray for a refrigerator comprising a pan having a bead on the top edge at one end, and a flat handle extending from said bead below the top thereof whereby drip on said handle from said refrigerator does not flow into said tray, said handle including a horizontal portion adjacent said bead, a vertical portion depending from said horizontal portion, and a lower horizontal portion ex-
- tending from said vertical portion to said pan, and a vertical sealing cover secured to said vertical portion of the handle.
- In testimony whereof I hereto affix my signature.
